UNITED STATES PATENT OFFICE

2,689,456

OPEN CYCLE GAS TURBINE AND CLEANING
MEANS THEREFOR

Roy B. White, Baltimore, Md., assignor to Bituminous Coal Research, Inc., Washington, D. C., a corporation of Delaware

Application June 22, 1951, Serial No. 233,021

5 Claims. (Cl. 60—39.46)

1

This invention relates to multi-stage axial flow gas turbines incorporating means for effecting cleaning of fouled last stage blading elements.

In the operation of multi-stage axial flow gas turbines, and particularly those used in systems wherein the motive fluid is generated by the pressurized combustion of pulverized coal, it has been found that, in an open-cycle system wherein the turbine exhausts directly into the atmosphere, there is a localized fouling of the last stage rotor blades by deposits of a sooty nature. This condition is associated with the operation of turbines wherein the combustors are of the cold walled type and continuously-burning oil flames are used to insure positive ignition of the pulverized coal-air flame. Where gas turbine power plants utilizing motive gas generated from the pressurized combustion of pulverulent solid fuels are used in locomotives, variations in locomotive speed are obtained by varying the rate of feed of pulverulent solid fuel to the combustor.

It has been noted that under conditions of locomotive operation where there are a multiplicity of starting periods and decelerating or stopping periods, deposits of a sooty nature are deposited only on the last stage rotor blades of the multi-stage axial flow turbine. These deposits are readily removed by hand tools, but such cleaning operation requires the dismantling of at least the discharge end of the turbine casing in order to permit access to the fouled rotor blades.

It has now been found that the fouling on the last rows of multi-stage axial flow gas turbine rotor blades can be removed without opening the casing by providing means for directing jets of vaporous fluids against the fouled portion of the affected blades. This is essentially effected by providing symmetrically disposed jet devices mounted in the turbine casing and directed against the last row of rotor blades. The devices used may comprise a long single nozzle extending the length of and in radial alignment with the radially disposed rotor blades. The cleaning may be effected by injecting fluid through such nozzles, which, as noted, are juxtaposed to the affected blades so that the jets of fluid are projected against the fouled surfaces of the blades as they severally rotate past the fixed nozzles. The fluids used may comprise hot or cold air, steam, and water, with or without cleaning agents, as well as suitable solvents. Instead of a long single nozzle in the jet devices, a multiplicity of aligned small nozzles may be used. The cleaning fluid may be supplied from a separate source, or where air is used, may be supplied from the air system of the

2

turbine plant, particularly in view of the fact that the greatly reduced pressure obtaining in the discharge end of the turbine will permit the use of low powered jets.

It is, therefore, among the features of novelty and advantage of the present invention to provide improved means for cleaning fouled last stage rotor blades of multi-stage axial flow gas turbines which are powered by motive fluid generated in pressurized combustors utilizing fuels which liberate applicable amounts of solid residues.

It is also a feature of novelty and advantage of the invention herein to provide multi-stage axial flow gas turbines incorporating means for cleaning fouled last stage rotor blades, as well as control means for operating the cleaning means, which means are operable from a central panel or control board.

The above and other desirable features of novelty and advantage will be more readily appreciated by reference to the specification and accompanying drawings, certain preferred embodiments of the invention being shown, by way of illustration only, as it is not intended to be limited to the specific form illustrated, except as such limitations are clearly imposed by the appended claims.

In the drawings, like numerals refer to similar parts throughout the several views, of which

Fig. 1 is a schematic showing of a pulverulent fuel burning gas turbine power plant;

Fig. 2 is a fragmentary detail of the low pressure end of a gas turbine rotor having five stages of turbine blades and showing the location of fouling deposits on the last stage blades;

Fig. 3 is a fragmentary section of the low pressure end of a multi-stage blading gas turbine with parts of the casing removed to show the mounting of the cleaning jets with respect to the last stage of blading;

Fig. 4 is a schematic view illustrating the mounting of a cleaning jet with respect to a rotor blade;

Fig. 5 is a perspective of a cleaning jet having a single nozzle slot, and

Fig. 6 is a view similar to Fig. 5, showing a plurality of aligned jets in the cleaning nozzle.

Referring now to the drawings, there is shown a gas turbine power plant adapted for the generation and use of motive fluid prepared by the pressurized combustion of pulverized coal fed to a combustor as a streaming entrainment of solid fuel particles in a combustive air stream and which system includes coarse and fine ash separators in the gas discharge line from the com-

bustors, the clean gas being delivered to a use device such as a gas turbine, which discharges its exhaust to the atmosphere through a regenerator wherein compressed air supplied by a main air compressor driven by the gas turbine, is pre-heated and supplied to the combustor to be heated further, by the burning of the fuel, to form the turbine motive fluid.

As shown in Fig. 1, suitable generators are coupled to the turbine output shaft. The power plant illustrated schematically in Fig. 1 is of the type shown and claimed in Patent No. 2,533,866, issued December 12, 1950, to John I. Yellott.

Considering the specific details of the present invention and with more particular reference to Figs. 3 to 6, there is shown a turbine casing 10 mounting a rotor 11, incorporating multiple rows of blades, and having a last row of blades, severally indicated by the numeral 12. Pairs of jets 13 are mounted, 180 degrees apart, in the rotor casing with the nozzles directed against the last stage or terminal row of blades 12. The jets 13 may be secured in the casing in any suitable manner and are connected to a feed line 14, mounted in the casing wall, which line is connected to a suitable fluid supply 15, comprising a cleaning fluid tank and pump, as shown in Fig. 1. As shown more in detail in Figs. 2 and 4, the sooty deposit 16, described above, is localized and will form mainly at the trailing edges of the convex surfaces of the terminal rotor blades 12. The jet of cleaning fluid 17 issuing from the nozzle 13 will sweep the rotating blades 12, and remove the deposits 16. By providing two or more symmetrically arranged jets the terminal or last stage blades are subjected to an accelerated scouring action which serves to remove the deposits more readily. As shown in Fig. 5, the jet of fluid may be produced by a longitudinal slot 18 in jet 13. An alternate form, as illustrated in Fig. 6, comprises a longitudinal array of apertures or small nozzles 19. The fluid introduced through line 15 may comprise air, water, or steam, and the like, from external sources. Alternatively, air may be taken from the main compressor.

The cleaning of the fouled blades is best effected when the turbine is operating at low speeds, as during the starting and stopping operations. Under such low speed conditions, the jets are much more effective in reaching the blade surfaces than when the rotor is turning at high speeds, and the motive fluid is issuing from the blade passages at high velocity.

The jets, as previously noted, are preferably mounted symmetrically, in radial juxtaposition to the last stage rotor blades, to eliminate the unbalance which would result from the presence of a single jet or unsymmetrically disposed multiple jets.

It will now be appreciated that there has been provided a novel apparatus for cleaning fouled last stage turbine blades of multi-stage axial-flow gas turbines of pulverized coal burning power plants, which cleaning apparatus requires but a minimum of structure and without requiring any alteration of existing turbine structures or designs.

What is claimed is:

1. In an axial flow gas turbine power plant comprising pulverized coal supply means, a pres-

surized combustor, a pressurized air line and a compressed air supply therefor, means for transferring pulverized coal into the air line whereby to form a combustive fluid, means for feeding the combustive fluid to the combustor, and a multi-stage axial flow gas turbine in fluid communication with the combustor, the improvements comprising jet means in the turbine casing effective to direct cleaning blasts against the last stage rotor blades, and cleaning fluid supply means coupled to said jet means, whereby said last stage rotor blades are cleaned while the turbine is in operation.

2. Multi-stage axial flow gas turbine according to claim 1, characterized by the fact that the fluid supply means comprises an air line coupled to the compressed air supply.

3. In a multi-stage axial flow gas turbine characterized by the fouling of the last stage rotor blades with sooty deposits, the improvements comprising jet means juxtaposed to the last stage rotor blades, and means for supplying a cleaning fluid to said jet means, whereby the fluid is projected against the fouled blades and the blades are cleaned while the turbine is rotating.

4. In a self-purging, open-cycle multi-stage axial flow gas turbine for use as the prime mover in generating electric locomotives and particularly adapted for use with motive fluids which deposit fouling material on the last stage rotor blades, the improvements comprising jet cleaning means symmetrically mounted in the turbine casing in radial juxtaposition to the said last-stage rotor blades, and cleaning fluid supply means coupled to said jet cleaning means, whereby the cleaning fluid is projected against the last stage rotor blades, and the blades are cleaned while the turbine rotor is rotating.

5. In a generating electric locomotive including generators powered by a multi-stage axial flow gas turbine, and a motive fluid generator for the turbine, the motive fluid being characterized by the deposition of fouling material on the last stage blades of the turbine rotor, the improvements comprising jet cleaning means symmetrically mounted in the turbine casing in radial juxtaposition to the said blades, and cleaning fluid supply means coupled to said jet means, whereby cleaning fluid is discharged against the fouled blade surfaces and the surfaces are cleaned while the turbine rotor is rotating.
